UNITED STATES PATENT OFFICE

GEORGE S. COOPER, OF PROVIDENCE, RHODE ISLAND

SPRING DOOR CATCH

Application filed July 18, 1928. Serial No. 293,684.

This invention relates to spring door catches and has for its chief object to produce a highly efficient and satisfactory catch which will automatically adapt itself to the shrinking or swelling of the door, or frame, or both, to which the catch may be applied, whereby changing weather conditions will not impair its proper functioning. To this end the catch, which comprises cooperating members, one of which is provided with a pair of resilient jaws and is preferably carried by a fixed frame member, and the other member comprising a nosing element which may be thrust between the jaws and be held yieldably thereby, and preferably carried by the door, is so constructed that the two members may properly cooperate even though they may on initial contact be relatively displaced laterally of their normal path of catching and releasing movement. Thus the two members are so constructed that initial engagement between them, even when these are considerably displaced laterally from normal, tends to produce a relative correcting movement, so that when the door is fully closed, they are in normal fully engaged position. At least one of the members is so mounted that it may be moved in either of opposite directions by the other to effect such correction, but it has a tendency to resume a normal position relative to its supporting object when unsubjected to a correcting force. At least one of the members, therefore, may be spring supported so as to yield laterally in either of opposite directions when contacted eccentrically by the other and so as to be moved into normal catching position as the door approaches closed position.

For a more complete understanding of this invention, reference may be had to the accompanying drawings, in which

Figure 1 shows in perspective one construction of one of the cooperating members of the catch.

Figure 2 is a perspective illustrating the manner in which the construction of Figure 1 may be formed.

Figure 3 is a fragmentary section showing the catch as applied to a door and its casting, the door being shown as slightly open.

Figure 4 is a similar view showing the door closed.

Figure 5 is a view similar to Figure 3, but showing in full lines the relative positions of the parts when the door has become swollen, the dotted lines indicating the action of the catch parts when such a door is more nearly closed.

Figure 6 shows in perspective one form of nosing member shaped to cooperate with the member shown in Figures 1 and 7 to 15.

Figure 7 is an elevation showing a different form of jaw member.

Figure 8 is a section on line 8—8 of Figure 7.

Figures 9 to 12 are views in pairs similar to Figures 7 and 8, respectively, but showing further modifications, Figures 10 and 12 being sections taken on the correspondingly marked section lines on Figures 9 and 11, respectively.

Figure 13 is a section on line 13—13 of Figure 14, showing a further modification.

Figure 14 is an elevation of the device shown in Figure 13.

Figure 15 is a section similar to Figure 13 but showing still another modification.

Referring to the drawings, Figures 1 to 5 illustrate the catch members in their preferred form. One of these catch members, shown detached in Figure 1, comprises a plate 1 having spring finger portions 2 partially severed from opposite ends thereof, each spring finger portion, as shown, being provided with a hole 3 adjacent to its free end to receive a screw or other suitable fastening means by which it may be fixed in position. Between the fingers 2 the plate 1 is partially severed to form a central tongue 4 and an intermediate looped tongue 5. The tongue 4 is bent to form a hump portion 6 about midway of its length, being inclined downwardly at 7 and having its free end portion upwardly turned at 8. The loop tongue 5 is shown as substantially flat except at its forward end, which is downwardly turned at 9. This catch member may be cut from a single plate of spring metal, being slotted at 12 to partially separate the finger members 2 from the body of the plate and having a substantially

85

90

95

100

105

U shaped cut 14 therein to define the outer edge of the tongue 4 and the inner edge of the tongue 5. In order to facilitate this cutting of the spring plate without danger of cracking it during the cutting operation, it is preferable to form holes 15 to define the inner ends of the cuts. This member of the catch may be cut and formed at a single dieing operation.

10 The cooperating member of the catch comprises a nosing, which as shown in Figures 3, 4 and 5, may comprise a single strip of spring metal 20 doubled on itself, the end portions being provided with perforations to receive 15 attaching screws 22, the intermediate loop portion being bent at substantially right angles to the ends as at 23 and formed at its outer end where the metal is folded with an enlarged bead 25. This bead presents a 20 rounded edge for engagement with the spring jaws 4 and 9 and the ends of these spring jaws are curved away from each other so that they act to center the bead 25 should it strike them in the closing movement of the door 25 somewhat eccentrically.

The spring fingers 2 support the jaw members spaced from the member to which the jaws are attached, herein shown as a door casing member 30, and permit the jaws to yield 30 toward and from the adjacent face of the member 30 so as to conform to the position of the nosing member when the door is closed. As shown the nosing member is fixed to the door 31.

35 The nosing member may be made stiffer by forming it as shown in Figure 6, in which one end portion of the strip is shown as flat at 35 to bear firmly against the door and is then bent outwardly at right angles therefrom as 40 at 36. The other end portion of the nosing inwardly of the bead 37 engages the portion 36 for a limited extent as at 38 and then is bent away therefrom to form a stiffening strut 39, which extends to the portion 40 45 overlying the portion 35. The portions 40 and 35 are fixed together by the attaching screws which fix the nosing to the door. Thus a very stiff construction is provided which tends to resist displacement of its bead 50 portion 37.

In normal position of the nosing and jaw members, the path of movement of the bead portion 25 (or 37 in the construction of Figure 6) is in alignment with the space between the jaws, as shown in Figures 3 and 4, so that the spring fingers 2 are substantially unflexed during the closing and opening movements of the door. When, however, the door swells so that the nosing member is brought 60 closer to the face of the casing member 30, the bead portion 25 strikes the forward end of the jaw member 9, causing the spring fingers 2 to be flexed so as to permit the nosing to center between the jaws, this being shown in 65 Figure 5. Thus the jaw members are moved

automatically into proper alignment with the nosing even though the initial contact between the members is out of proper alignment. Similarly should the door shrink from its normal position, the nosing will strike the curved 70 end of the jaw member 4, whereupon the spring fingers 2 will flex sufficiently to permit the jaw member to properly engage with the nosing member.

The jaw members may be variously constructed, certain constructions other than that shown in Figures 1 to 5 being shown in Figures 7 to 14. For example, in Figures 7 and 8, the plate 50 is cut to form integral spring 80 supporting fingers 51 and one jaw member 52, the other jaw member 53 being formed as a separate piece which is fixed to the rear portion of the plate 50 in any suitable way as by spot welding or riveting at 54.

In Figures 9 and 10, the spring support 85 for the jaws comprises a single strip element 60, which is shown as made wider at its forward end, as at 61, to receive attaching screws or other means 62 on opposite sides of the end portions of the jaws. This strip 60 90 is shown as raised up slightly from the level of its supporting portion immediately back thereof as at 63 to form a free spring portion and it is then bent forwardly as at 64, its forward end being brought over its attaching 95 end portion and forming one of the jaw members as at 65. The other jaw member 66 is shown as formed as a separate piece, which is riveted or otherwise attached to the other jaw portion 65 as at 67.

100 Instead of forming the spring supporting portions so that they are attached adjacent to the free ends of the jaws, they may be attached rearwardly thereof, such a construction being shown in Figures 11 to 14. In Figures 11 and 12 a strip 70 is shown as bent downwardly as at 71 adjacent to its rear end and then straight rearwardly as at 72, where it is provided with perforations or slots to receive the attaching screws or other fasteners 73. The forward portion of this strip is slit as at 74 to form a pair of spring jaw members 75, which together form one of the jaw members, herein shown as the lower member, and an intermediate jaw member 76, which, as shown, is bent to form the other or upper jaw member.

110 In Figures 13 and 14 the spring strip 80 is formed at its rear end similarly to the strip 70 of Figures 11 and 12, but its entire forward 115 end is shaped to form one of the jaw members, as the lower jaw member 81, and the other jaw member is formed as a separate piece as 82 fixed to the jaw member 81, as by rivets 83, by spot welding or other suitable 120 means.

125 In Figure 15 a still further modification is shown in which the jaw members are spring supported by being attached to the rear end of the spring finger 90, as by means of the rivets 130

91 and the jaw members themselves are shown as formed of separate resilient strips 92 and 93 fixed together as at 94.

In each of the constructions shown it will be noted that the jaw members will be carried by the spring fingers normally spaced from the supports by which they are carried so that the jaws can yield laterally in either of opposite directions, opposite ends of the supporting spring fingers being for this purpose normally in different planes.

In all of the constructions illustrated, it will be seen that one of the engaging members has a spring element for carrying its opposite member-engaging portion, this spring element being offset from the path of relative movement of the members and fixedly secured beyond the offset portion sufficiently remote from the opposite-member-engaging portion 20 to act as a resilient lever of substantial length lying in the general direction of the spring jaws and permitting bodily deflection of this portion toward and from the plane of securement of the element. This lever may be continuous in one general direction as in the form shown in Figures 11, 12, 13 and 14 or it may be turned back on itself either in the same or a different plane as shown in Figures 1 to 10 and 15.

25 In all of these constructions therefore the jaws are movable as a unit into alignment with the nosing when the nosing is brought into engagement with either of the jaws.

Having thus described certain embodiments of this invention, it should be evident to those skilled in the art that various changes and modifications may be made therein without departing from its spirit or scope as defined by the appended claims.

30 I claim:

1. A catch member comprising a plate having partly severed end portions forming spring supporting fingers fixed at the severed ends, the intermediate portion of said plate 45 being severed to form a pair of spring jaws spaced to have a mating catch member snapped therebetween.

2. A catch member comprising a plate having partly severed end portions forming 50 spring supporting fingers fixed at the severed ends, the intermediate portion of said plate being severed to form a pair of spring jaws spaced to have a mating catch member snapped therebetween, said fingers and jaws 55 being cut from the same side portion of said plate.

3. A catch member comprising a pair of spring jaws fixed together at one end and shaped to receive and retain between them a 60 mating member pushed therebetween from the other free end, and a leaf spring fixed at one end and carrying said jaws at their fixed ends at the other end, said leaf spring having its fixed end adjacent to the free ends of said 65 jaws.

4. A door catch comprising a pair of separable members movable relatively in a path into and out of engaging relation, one of said members being attachable to a door and the other attachable to the casing for said door, one of said members comprising a pair of spaced jaws between which the other of said members may engage and a leaf spring supporting both jaws at one end, the other end of said leaf spring being offset and fixed, said spring presenting a resilient portion of substantial length substantially parallel to said path, whereby said jaws may be moved as a unit transverse to said path in either direction from a normal position to adjust themselves into proper alignment with the other of said members.

In testimony whereof I have affixed my signature.
